108,644

DESIGN FOR A LOUVER FOR LIGHTING FIXTURES

James T. Holmes, Jamaica, N. Y., assignor to Shapiro & Aronson, New York, N. Y., a corporation of New York

Application February 24, 1937, Serial No. 67,824

Term of patent 3½ years

To all whom it may concern:

Be it known that I, James T. Holmes, a citizen of the United States, residing at 168-11 Highland Ave., Jamaica, L. I., have invented a new, original, and ornamental Design for a Louver for Lighting Fixtures, of which the following is a specification, reference being had to the accompanying drawing, which forms a part thereof, in which:

Fig. 1 is a perspective view of a louver for lighting fixtures showing my new design; and Fig. 2 is a bottom plan view thereof.

The characteristic features of my design are of the graduated height and spacing of the rings and the shape of the radial baffles with the curved portions projecting below the straight lines between the rings, so that, viewed in perspective, a plurality of curves are seen at different angles.

I claim:

The ornamental design for a louver for lighting fixtures substantially as shown and described.

JAMES T. HOLMES.
